Emil Schwartz

UNITED STATES PATENT OFFICE

98,118

DESIGN FOR AN ENSEMBLE DRESS

Emil Schwartz, New York, N. Y.

Application November 18, 1935, Serial No. 59,625

Term of patent 3½ years

To all whom it may concern:

Be it known that I, Emil Schwartz, a citizen of the United States of America, residing in Manhattan, county of New York, and State of New York, have invented a new, original, and ornamental Design for an Ensemble Dress, of which the following is a specification, reference being had to the accompanying drawing, forming part thereof, wherein,

Figure 1 is a front view of an ensemble dress showing my new design.

Figure 2 is a rear view of the ensemble dress shown in Figure 1.

Figure 3 is a front view of the dress unit of the ensemble dress shown in Figure 1.

Figure 4 is a rear view of the dress unit of the ensemble dress shown in Figure 3.

The motifs on the front and back of the jacket member of the ensemble are cut-out petal shaped elements surrounded by embroidery.

The solid area extending around the collar of the dress member of the ensemble represents a contrastingly colored edging.

The circular elements extending down the waist portion of the dress, represent buttons.

The triangular structures extending down from the back collar portion of the dress, represent cut-out areas.

I claim:

The ornamental design for an ensemble dress, substantially as shown, and described.

EMIL SCHWARTZ.
